FLAP TRIMMER

Nicholas W. Mathey, Boston, Mass.

Application November 30, 1931, Serial No. 577,981

7 Claims. (Cl. 12—17)

This invention pertains to shoe manufacture and relates more particularly to a novel method and machine for use in skiving the edges of the breast covering flap of a Louis or similar heel preparatory to cementing or otherwise securing the flap in position. In order to provide a finely finished appearance at the lateral edges of the heel breast, it is customary in the preparation of the better grades of shoes to reduce the thickness of the breast flap along its edges before securing it in place. This operation has heretofore been performed laboriously and slowly by hand, or by the use of crude mechanism capable of skiving one edge only of the flap at one time, and then in a very inefficient and uncertain manner, and by reason of the care and skill required, this operation is too expensive for use except in shoes which sell at a high price. In certain types of shoes the material which covers the outer or lateral curved surface of the heel is lapped over against the breast surface, leaving the central part of the breast surface uncovered, and in order that the breast flap may have a smooth surface when cemented in place, it is very desirable to confine the skiving or thinning operation to that part of the flap which will overlie the lateral edges of the breast surface, leaving the central part of the flap of normal thickness. This is further desirable since the flap is thus less liable to contract and draw away from the edges of the breast surface than were the flap to be made very thin throughout its entire extent.

In accordance with the present invention I provide a simple mechanism easily operable by persons but little skilled in machine operations, and which is designed to skive both edges of the flap at the same time, while leaving the central parts of its original thickness. This may be accomplished by advancing the flap endwise across a cutting edge, preferably by feeding or positively advancing only the edge portions of the flap, leaving the intermediate or central portion free of the feeding or advancing means, while maintaining these edges in such spaced relationship as to cause the intervening or central section of the flap to bow or flex away from the cutting edge so as to clear the latter. The area of the skived edges may be predetermined and controlled definitely by confining the central portion of the flap to the desired transverse curvature.

A machine for these purposes may comprise a feed roll and a presser-foot cooperating to advance material across the cutting edge of a rotary cutter, the presser-foot being shaped and positioned to press only the lateral edges of a breast flap,

for example, firmly against the feed roll in the aforementioned spaced relationship, this presser-foot having an arcuate or otherwise curved intermediate portion for receiving and confining the central portion of the flap. Preferably the cutter and the presser-foot are maintained in a substantially fixed relationship while the feed roll is yieldably held in a predetermined position to be movable away from the cutter under relatively slight and abnormal increase in pressure such as might be caused by variations in material, so as to enable the feed roll to come into firm engagement with the material. This relatively fixed arrangement of the cutter and the presser-foot avoids uneven or irregular cuts of variable extent and this, together with the guiding feature of the presser-foot makes it possible to skive both edges of a flap simultaneously and yet to obtain uniform and accurately skived edges which will fit neatly along the edges of the breast surface of a heel. Preferably the machine also includes provision for adjustment whereby the width of the skived area may be varied at will.

In the drawings:

Fig. 1 is a side elevation of a skiving machine illustrating the manner in which the breast flap of a sole may be skived on this machine;

Fig. 2 is an end elevation of the machine shown in Fig. 1;

Fig. 3 is a section along the lines 3—3 of Fig. 2 with parts omitted and broken away and illustrating the position of the sole of a shoe while the breast flap thereof is being skived;

Fig. 4 is a detailed vertical section taken longitudinally through the feed roll and the presser-foot of the machine shown in the preceding views;

Fig. 5 is a combined edge and bottom plan view of an unattached sole having the breast flap thereof turned down to illustrate the manner in which the edges thereof have been skived by the machine;

Fig. 6 is a transverse section through the breast flap taken along the line 6—6 of Fig. 5;

Fig. 7 is a side elevation of a shoe in inverted position showing the breast flap in place on the heel; and

Fig. 8 is a section along the line 8—8 of Fig. 7.

In the apparatus selected for illustration herein and by way of example, a feed roll 10 (Fig. 4) is disposed closely adjacent the traveling cutting edge 11 of a cylindrical cutter 12, and a presser-foot 13 extends longitudinally of the feed roll and along the cutting edge. These parts are supported in operative relation in a frame comprising a box-like lower housing having side walls 110

14 and 16 and a top or table portion 17 (Fig. 3). Near the rear side of the machine a post 18 is mounted on the table and is provided with a horizontal arm having at its forward end a head 19. A plunger rod 21 is mounted for vertical movement in this head and normally is urged downwardly under the action of a relatively strong spring 22, the latter being disposed within a recess or bore in the upper end of the rod and being held under compression by a thumb screw 23 which is threaded through the upper side of the head and engages a movable seat 24 for the upper end of this spring. Downward movement of the plunger rod 21 is limited by abutment means comprising a stud 26 which is rigid with the upper end of the plunger and extends freely through an opening in the upper side of the head. A thumb nut 27 is threaded on the upper end of this stud and is adapted to engage the upper side of the head to limit downward movement of the plunger rod.

The presser-foot 13 comprises an arcuate portion which overlies the feed roll and a connecting arm 29 which is mounted to pivot at 31 on the lower end of the plunger rod. Another arm 32 is rigidly connected to the arm 29 as by being integral therewith, as shown, and extends upwardly to engage an adjustable abutment provided in the present instance by an adjusting screw 33 which extends transversely through the body of the plunger rod and has threaded engagement therewith, a lock nut 34 is provided for securing the screw in any desired position of adjustment. The arm 32 is urged yieldably against the outer end of the adjusting screw 33 by a leaf spring 36 which may be mounted upon the head 19 or in any other convenient position.

A roller 37 is mounted upon the lower portion of the plunger rod and is receivable in a notch or complementary recess formed in the forward end of a lever 38, the latter preferably being mounted to pivot intermediate its ends on a fulcrum pin 39 carried by a bracket 41 mounted upon the table portion 17. This lever extends to the rear side of the machine where it may be operated manually to raise the plunger rod 21 or it may have a connection 42 for operation by a treadle (not shown). The under side of the presser-foot is generally concave and follows a curve somewhat similar to the longitudinal curvature of the feed roll, but preferably of greater curvature than the latter, the central portion of the under side of this presser-foot being recessed or cut away to provide an offset portion 43 and spaced end portions 44 and 46.

The feed roll 10 is rotatably supported upon a shaft 47 (Fig. 1) carried by a horizontal arm 48. This arm is carried by a tiltable frame comprising an elongate member 49 (Fig. 2) which extends transversely of the machine and is supported at its ends on pivot bearings 51 and 52, the latter being carried by the side walls 14 and 16 respectively. In order to provide for tilting the feed roll longitudinally, the arm 48 (Fig. 1) is rotatably supported in a bearing 53 carried by the member 49. The arm 48 extends outwardly beyond this bearing and is fixedly connected to an arm 54 which curves downwardly (Fig. 2) and carries at its lower end an adjusting screw 56. The frame member 49 has a rigid depending arm 57 providing a seat 58 against which the adjusting screw is adapted to engage. A coil spring 59 extends between the arms 54 and 57 and is held under the desired tension by an adjusting screw 61 mounted in suitable bosses

62 and 63 provided in the arms 57 and 54 respectively, a head 64 on screw 61 being provided for adjusting the tension of the spring 59.

At some convenient point, as at the left-hand end (Fig. 2) of the member 49, a rigid arm 66 extends downwardly and is pivotally connected at its lower end to an eye bolt 67 (Fig. 1). The latter extends freely through a lug 68 formed on the frame and is fitted at its outer end with a thumb nut 69. A relatively weak coil spring 71 is connected to the pivot pin 72 which forms the connection between the eye bolt and the arm 66 and to a fixed abutment means 73. It will be seen that as the frame member 49 is tilted about the pivots 51 and 52, the feed roll may be moved in a clockwise or counterclockwise direction as viewed in Fig. 1. The relatively weak spring 71 tends normally to swing this roll in a counterclockwise direction, but this tendency is opposed by engagement of the thumb nut 69 with the lug 68, these parts constituting an abutment means for positively and definitely limiting upward movement of the feed roll, while the yieldable connection provided by the spring makes it possible for this roll to move downwardly or in a clockwise direction, as viewed in Fig. 1, under the influence of relatively slight increase in pressure, such as that due to variations in thickness of material, and assures a firm engagement of the feed roll with the work at all times.

It will also be understood that by adjusting the thumb screw 56 and the lock nut 55 the feed roll may be tilted longitudinally, as viewed in Fig. 2. The feed roll is provided with a universal connection 76 adapted to be driven by any suitable source of power (not shown). The cutter is mounted upon a shaft 77 which is rotatably supported in bearings (not shown) mounted within the housing. This shaft extends beyond the rear side of the machine and carries a pulley 78 which may be driven in any approved manner.

In the manufacture of shoes of the class described it is customary to provide the outer sole 80 (Fig. 5) with a flap 81 of a size to cover the breast surface of a heel; usually the flap is formed by slitting or cutting under the grain surface of the sole to separate the thin layer from the rear end of the sole to a point beyond the heel seat. The sole and the shoe upper are then attached together and the flap is turned back as illustrated in Fig. 5 to permit a heel to be attached to the heel seat. This having been done, the flap is fitted over the breast surface of the heel as illustrated in Fig. 7, a last 82 being in the shoe at this stage of the procedure. As the breast surface is ordinarily concave, it is highly desirable to thin down the edge portions of the flap so that the inner surface thereof may be substantially complementary to the heel breast and fit smoothly thereover. Moreover, in certain grades of shoes, the outer surface of the heel is covered with relatively thin finishing material 83 (Fig. 8) which is commonly folded or secured around the vertical edges of the breast surface as indicated at 84 and 86. These inturned edges of the finishing material leave an abrupt depression across the central portion of the heel breast and add considerably to the difficulty of providing a neat, snugly fitting and good appearing covering for this surface. Heretofore, in the more expensive shoes, the edges of the flap have been skived down by hand to leave a relatively thick central portion with thinner marginal portions to provide the desired complementary relation-

ship requisite for a well fitting flap. Obviously this operation requires considerable skill and as it is performed by hand it adds materially to the cost of a shoe. Moreover, the workmanship depends largely upon the ability or skill of the individual workman.

The machine of the present invention provides for performing these operations substantially automatically in a manner which requires very little skill on the part of the workman. In using this machine the feed roll and presser-foot are adjusted to receive a flap of the particular thickness and dimensions employed. From Fig. 4 it will be seen that the feed roll has substantially the same curvature longitudinally as the cutter while the under side of the presser-foot has a curvature of less radius so that the end portions 44 and 46 of this member may be adjusted to protrude across the cutting edge and yet leave an opening between the cutter and the intermediate section of the presser-foot through which the central portion of a flap may pass without engaging the cutting edge. The presser-foot is set at the proper position relative to the cutter to press the marginal portions of a flap across the cutting edge just far enough to assure skiving of the precise area which it is desired to remove, this of course being determined partly by the shape of the particular presser-foot selected for use. The adjusting screw 33 is set positively to limit upward movement of the presser-foot about its pivot 31 and the thumb nut 27 is turned down on the stud 26 until it comes solidly into engagement with the upper surface of the head 19. These adjustments having been made, further downward movement of the rod 21 and upward pivotal movement of the presser-foot are positively precluded.

The screw 23 is also adjusted to place the relatively strong rigid spring 22 under sufficient tension so that normally this spring functions as a substantially rigid member or connection, and is adapted to yield only under relatively heavy pressure such as would inevitably result in damage to the apparatus by breakage or rupture of parts. This arrangement therefore affords the advantages of a rigid supporting structure making it possible definitely to predetermine the position of the presser-foot and thus to assure accurate skiving while precluding the possibility of damage as by jamming of some of the parts or of material.

The axis of the feed roll may be tilted longitudinally (by setting the adjusting screws 56 and 64 as will be understood) to bring the curved feeding surface of this roll into alignment with the cutting edge. Once this adjustment has been made, it is not altered by bodily movement of the feed roll due to tilting or rocking of its supporting frame about the pivot bearings 51 and 52. The correct minimum spacing of the feed roll from the cutting edge is secured by adjusting the thumb nut 69 to permit the relatively weak spring to swing the supporting frame to the desired position, further movement of course being prevented by engagement of the nut 69 with the frame lug 68. Preferably this adjustment is so made that the feed roll engages the work with a yielding pressure under the action of the weak spring which also permits the feed roll to retract downwardly or away from the cutting edge under slight increases in pressure such as may be caused by variations in thickness of the work.

This construction and relative arrangement of parts provides for feeding the rough or unfinished

side of a heel flap and for forcing the grain surface thereof firmly against the smooth under surface of the presser-foot. As the latter remains rigid and immovable during normal operation it will be seen that it provides for definitely gauging the thickness and surface contour of the flap.

After the various adjustments have been made, the shoe is placed in an upright position above the table (Fig. 1) with the flap 81 turned forward so that the grain surface of the leather faces the presser-foot. The presser-foot is then lifted by actuation of lever 38, preferably by means of a foot treadle and the free end of the flap is then inserted between the feed roll and the presser-foot whereupon the presser-foot is allowed to drop. The machine being in operation at this time, the flap is advanced by the feed roll and pressed or crowded against the presser-foot, the action being such that the oppositely inclined outer edges of the feed roll press the marginal portions of the flap firmly against the end portions 44 and 46 of the presser-foot at an inclination which crowds the central portion of the flap upwardly, causing this central portion to flex or bulge outwardly and substantially fill the recess or offset portion 43 which confines the central portion of the flap to a well defined contour and assures accurate skiving of the edges over an area predetermined by the shape of the presser-foot. The central portion of the flap is thus caused to draw away from the upper side of the cutting edge so that only the edge portions protrude across this cutting edge and are skived by the latter as indicated at 88 and 89 (Figs. 5 and 6). The presser-foot illustrated in the drawings is shaped to skive the edges to fit over the inturned marginal portions 84 and 86 of the heel covering 83 as illustrated in Fig. 8, but it will be understood that for different types of heels, as for example, those which have no covering material or which have covering material turned in to a greater or less extent, the proper surface contour may be provided by substituting a presser-foot having the desired shape. As the skiving operation proceeds, the material skived from the edges passes within the cutter as indicated at 87 in Fig. 1 and when this operation is completed the lever 38 is depressed either manually or by means of a treadle to lift the presser-foot and thereby release the flap from the action of the feed roll. The shoe is then removed, the heel attached and the flap secured in place as in the previous procedure. The portions of the marginal edges which project beyond the vertical edges of the breast surface may be trimmed down in any approved manner.

The adjustable and yieldable mounting for the feed roll and the substantially fixed relationship between the presser-foot and the cutter are also highly desirable features as they make it possible to predetermine and to gauge accurately the area to be skived, but it will be apparent that many of the advantages of the present invention may be gained from apparatus of this character having a yieldably mounted presser-foot which may co-operate with a fixedly or yieldably supported feed roll.

It should be understood that the present disclosure is for the purpose of illustration only and that this invention includes all modifications and equivalents which fall within the scope of the appended claims.

I claim:

1. A skiving machine for simultaneously skiving the lateral margins of a heel covering flap forming an integral part of a shoe sole, said ma-

- chine comprising a cutter having a traveling cutting edge operable through a predetermined and substantially invariable path, a substantially rigid non-yieldable traveling surface for feeding the flap to said cutting edge, yieldable means for supporting said traveling surface for relative movement toward and from said cutting edge to accommodate flaps of different thickness, the path of travel of said traveling surface being approximately normal to said cutting edge and on one side thereof, presser means for holding the edge portions of the flap in engagement with said traveling surface and for causing the central portion of said flap to be deflected to the other side of said cutting edge, means for maintaining the pressed means substantially rigid and firmly in a predetermined position during normal operation but providing for relative separating movement of said latter means and the cutter in response to excessive and abnormal pressure, whereby damage to the machine may be avoided, and means for separating the pressure means from the cutter at the end of the skiving operation.
25. 2. Apparatus for simultaneously skiving the opposite lateral margins of a heel covering flap forming an integral part of a shoe sole, said apparatus comprising a cutter, a presser-foot and a feed roll adjacent the cutter and spaced for feeding the flap to the cutter with opposite lateral margins of the strip protruding across the cutter to be skived thereby, movable supports for the presser-foot and the feed roll, abutment means for limiting movement of these supports in a direction to bring the presser-foot and the feed roll toward each other, a relatively strong spring for holding the presser-foot supporting means solidly against the abutment means during normal operation, this spring being yieldable to permit the presser-foot to retract under excessive pressure, a relatively weak spring for holding the feed roll supporting means against the abutment means, this spring being adapted to yield to permit the feed roll to retract in response to relatively slight variations in pressure due to variations in thickness of material, and means for raising the presser-foot at the completion of the skiving operation whereby to permit the flap to be withdrawn by movement opposite to the feeding movement.
30. 3. That method of skiving a heel breast covering flap at the rear part of the sole of a lasted shoe so as to provide the flap with thin lateral edges while leaving the intermediate portion of the flap unskived, which comprises imparting a feed movement to the sole during the skiving operation such as to advance the flap with its free edge forward relatively to rotary cutting means adapted simultaneously to skive the opposite lateral margin of the flap as the latter is advanced while keeping said margins confined between substantially rigid elements, keeping the intermediate portion of the flap which is to be skived out of the field of action of the cutting
35. means, and at the completion of the skiving operation releasing said lateral margins from confinement and retracting the flap from the field of action of the cutting means by movement of the sole in the opposite direction.
40. 4. That method of skiving the lateral edges of the heel breast covering flap of a sole on a lasted shoe while leaving an intermediate area unskived, which comprises doubling the flap back into substantially parallel relation to the bottom of the shoe, advancing the material of the flap relatively to the edge of a cylindrical cutter while confining the lateral edge portions of the flap between substantially rigid curved surfaces disposed within and without the cutting edge, respectively, but while leaving the intermediate area substantially unconfined, and by means of said curved surfaces applying forces to the material in opposite directions from the areas to be skived toward the intermediate area, whereby to cause the latter to bulge out of the field of action of the cutter while the edge portions are being skived, and when the skiving operation has been completed, separating the rigidly curved surfaces and retracting the flap from between them.
45. 5. That method of skiving the heel breast covering flap of the sole of a lasted shoe, which comprises doubling the flap back into substantially parallel relation to the shoe bottom, imparting a feed movement to the shoe so as to advance the flap endwise during the skiving operation relatively to skiving means, holding the opposite marginal portions of the flap in operative relation to the skiving means during said feed movement while keeping the central portion of the flap out of the field of action of the skiving means, and thereafter withdrawing the skived flap from the field of action of the skiving means by movement of the shoe in a direction opposite to said feed movement.
50. 6. That method of skiving the heel covering flap of a lasted shoe having an attached sole provided with a flap at its rear part, which comprises feeding forward the flap with its rear end in advance relatively to the edge of a cutting instrumentality, confining the lateral marginal portions of the flap while so feeding the flap forward whereby accurately to position said marginal portions during the cutting operation, and causing the intermediate portion of the flap to bulge out of the path of the cutting edge of said instrumentality during the skiving operation.
55. 7. That method of preparing the heel breast covering flap of a lasted shoe having an attached sole furnished with such a flap at its rear part, which comprises moving the flap endwise and concomitantly with such movement presenting both lateral edges of the flap to rotary skiving means whereby simultaneously to skive said lateral edge portions, and while so skiving said lateral edge portions keeping the intermediate portion of the flap out of the field of action of such skiving means.

NICHOLAS W. MATHEY.
